UNITED STATES PATENT OFFICE.

JOSEPHUS LIGET, OF POSEY TOWNSHIP, FAYETTE COUNTY, INDIANA.

BROOM-HEAD.

Specification forming part of Letters Patent No. **55,316**, dated June 5, 1866.

To all whom it may concern:

Be it known that I, JOSEPHUS LIGET, of Posey township, Fayette county, Indiana, have invented certain new and useful Improvements in Broom-Heads; and I do hereby declare the following to be a full, clear, and exact description of the same, reference being had to the accompanying drawings, and to the letters of reference marked thereon.

Figure 1 is a view of the socket, and Fig. 2 a view of the lower portion of the handle.

In Fig. 1, A represents a bell-shaped socket, made of tin or other suitable material, the upper end terminating in a ring or ferrule, B, which is provided with a thumb-screw, C.

In Fig. 2, D represents the lower portion of the broom-handle, which is flattened on opposite sides, near the end, and is constructed with a mortise, E.

To make a broom the stalks of the broom-

corn are inserted in the mortise E to the required quantity, when the handle is passed up through the ring B, bringing the broom-corn tightly into the socket A, when the handle is secured in position by the thumb-screw C.

Should the broom, from long wear, become loose in the socket the thumb-screw may be loosened and the broom drawn still closer within the socket.

Having thus fully described my said invention, what I claim as new, and desire to secure by Letters Patent, is—

The handle D, provided with the mortise E and the set-screw C, in combination with the socket A, all arranged substantially as set forth and described.

JOSEPHUS LIGET.
